UNITED STATES PATENT OFFICE.

ANNE LÖWENSTEIN WERTHEIM, OF LONDON, ENGLAND.

SELF-LEVELING COT, BUNK, COUCH, AND THE LIKE FOR USE ON BOARD SHIP.

1,084,915.

Specification of Letters Patent.

Patented Jan. 20, 1914.

Application filed November 12, 1912. Serial No. 730,975.

To all whom it may concern:

Be it known that I, ANNE LÖWENSTEIN WERTHEIM, a princess of the German Empire, residing at London, S. W., England, 5 have invented certain new and useful Improvements in Self-Leveling Cots, Bunks, Couches, and the like for Use on Board Ship, of which the following is a specification, reference being had therein to the accompanying drawing.

This invention relates to improvements in connection with self-leveling cots, couches, bunks and the like, for use on ship-board, and particularly relates to a type of cot or 15 the like, which is suspended from an overhead frame-work.

The object of my invention is to provide self-leveling means in the form of suitable toothed sectors or semi-circular castings or 20 the like which are fixed under the upper member of the outer frame-work with the teeth downward, and are adapted to travel upon toothed racks, at the head of supporting columns or standards, one at each end 25 of the bunk.

The further object of the invention is to provide means for controlling and adjusting the traverse of the toothed sectors along the supporting racks for the cot, such means 30 being designed to maintain the bunk or cot in an even or level position, parallel to the horizontal, notwithstanding the heaving or rolling of the vessel.

In operation, assuming the supporting 35 columns to incline say 30° from the perpendicular, the frame-work supporting the bunk will not be carried through so large an arc because as the supports incline in one direction the teeth of the semi-circular 40 casting engaging with the rack under the counteracting influence of the controlling means will travel along the said rack in the opposite direction thus tending to keep the suspended bunk independent of the motion 45 of the ship.

The controlling means which reduce to the nominal any slight impulse due to the momentum of the bunk and thereby prevent the same acquiring an excessive or increased 50 swinging motion consist of band brakes which are fitted at the four points at which the overhead frame-works are supported. The center of each brake drum preferably coincides with the radius center of the semi- 55 circular toothed casting.

It will be understood that this device may be applied to the inner framework as well as to the outer framework.

The method of mounting supporting and controlling a self-leveling cot or bunk for use on ship board in accordance with this my invention and the arrangement and construction of the several working parts will be fully understood by reference to the accompanying drawings wherein:—

Figure 1 is an end elevation of a ship's bunk clearly illustrating my improved method of mounting and supporting the same. Fig. 2 is a side elevation thereof and Fig. 3 is a plan of the inner and outer frame-work and their fittings. Fig. 4 is an end view of one of the band brakes employed for controlling the traverse of the toothed sectors.

For effecting the objects of my invention 75 I employ two relatively moving parts the one in the form of a toothed sector or semi-circular toothed casting *a* fixed to the outer frame *b* of the bunk and the other a toothed rack *b'* fixed to or forming part of the vertical column or support *c* fixed to the deck or floor of the cabin. The toothed sector or semi-circular casting *a* is mounted to engage with the teeth of the rack *b'* in such a manner that as the supporting columns *c* incline in one direction with the motion of the vessel the semi-circular toothed castings *a* will by the action of gravity travel along the toothed racks *b'* in the opposite direction to an extent limited by the controlling means 90 employed for maintaining the said toothed sectors or castings *a* in place on the racks. The partial lateral movement thereby acquired reduces the arc of oscillation of the bunk and tends to maintain the stability 95 thereof.

The controlling means consist of the band brakes *d* which encircle the drum *e* fixed to or forming part of the semi-circular toothed castings *a* and are devised with the object 100 of controlling the traverse of the toothed sectors *a* and destroying any accentuated swinging movement due to the momentum which the bunk may acquire from the motion of the ship. Furthermore, these band 105 brakes hold the toothed castings *a* in place upon the toothed racks. They are therefore made from flexible steel bands or other elastic material in order to allow for the variation in the relative positions of the semi- 110

circular castings and the supporting racks. The ends k k' of the band brakes are connected by pins l to a rod l' slideable in a hole in a boss p . This boss is mounted upon a stud q fitted in a hole in the hanger bracket m and formed with a circular groove q' with which engages the set screw p' to retain the same in place. The hanger bracket m is fixed to the roof m' of the cabin the 10 said slideable rod l' having a spiral spring n mounted on its shank and a screw threaded extremity n' upon which is passed a winged nut o whereby the brake pressure may be adjusted.

15 As seen in Figs. 2 and 3 the inner frame f may be supported on the outer frame by means of trunnions g whose swinging movement may be diminished by band brakes d' which encircle drums e' on the cross shaft h .

20 The rods i for supporting the bunk are fixed thereto at their upper ends as shown at j while their lower extremities may form part of the frame of the bunk. In lieu of supporting the inner frame in this manner the 25 same may be supported by means of toothed sectors and racks in a similar manner to

that already described with regard to the outer framework.

What I do claim as my invention and desire to secure by Letters Patent is:—

1. In cots, bunks, couches and the like for use on ship board, self-leveling means comprising toothed sectors and racks for supporting the cots and adjusting means for controlling the traverse of the said toothed sectors along the racks, substantially as described.

2. In self-leveling means for ships' bunks or the like, toothed racks carried by columns or standards, toothed sectors engaging therewith and fitted to the frame of the cot, band brakes, encircling drums carried by a shaft fitted to the traversing toothed sectors and adapted to control the traverse thereof substantially as described.

In testimony whereof I hereunto affix my signature in presence of two witnesses.

ANNE LÖWENSTEIN WERTHEIM.
